UNITED STATES PATENT OFFICE.

JOHN E. GAREIS, OF FLUSH, KANSAS.

RESILIENT WHEEL.

1,409,290.

Specification of Letters Patent. Patented Mar. 14, 1922.

Application filed February 3, 1921. Serial No. 442,182.

To all whom it may concern:

Be it known that I, JOHN E. GAREIS, a citizen of the United States, residing at Flush, in the county of Pottawatomie and State of Kansas, have invented certain new and useful Improvements in Resilient Wheels, of which the following is a specification, reference being had to the accompanying drawings.

10 This invention relates to improvements in resilient wheels and more particularly to a wheel of that type embodying inner and outer fellys, having arranged therebetween a cushioning element, the outer felly being provided with side plates engaging the inner felly to form an enclosure for the cushioning element.

20 An important object of the invention is to provide in a construction of this type an engagement between the inner felly and the side plates to effectually prevent the entrance of dirt and water to the cushioning element.

25 A further object of the invention is to provide in a device of the above character an outer felly which is formed of coacting annular sections which are separable to permit placing and removal of a tire or a demountable rim by which the tire is carried.

30 A further object of the invention is to provide in a device of this character a novel and improved cushioning element consisting in a continuous spring disposed intermediate the inner and outer fellys and embodying portions engaging the outer felly and portions engaging the inner felly arranged in staggered relation to those engaging the outer felly, the corresponding ends of the portions being connected by substantially radially extending portions of the spring.

40 Other objects and advantages of the invention will become apparent throughout the course of the following description:

45 In the accompanying drawings, wherein for the purpose of illustration is shown a preferred embodiment of my invention,

Figure 1 is a fragmentary side elevation of a vehicle wheel constructed in accordance with my invention, parts being broken away,

50 Figure 2 is a section on the line 2—2 of Figure 1,

Figure 3 is a section on the line 3—3 of Figure 1,

55 Figure 4 is a section on the line 4—4 of Figure 2,

Figure 5 is a section on the line 5—5 of Figure 3, and

Figure 6 is a fragmentary perspective of the outer felly and side plates attached thereto.

60 Referring now more particularly to the drawings, the numeral 10 indicates the spokes of a wheel to the outer extremities of which is secured an inner felly 11. Arranged about the inner felly 11 and normally concentric therewith when weight is removed from the wheel, is an outer felly 12. The inner felly 11 has secured to its peripheral face an annular steel band 13, the band being held in position by means of bolts 14 extending through the band and felly 11. The marginal edges of the band 13 are provided with upstanding flanges 15, and the band intermediate the flanges 15 has its outer surface transversely grooved at spaced intervals as indicated at 16. The marginal flanges 15 have extending therethrough bolts 17 transversely alining with the grooves 16 of the plate 13. These bolts have their heads countersunk in one of the flanges 15 as indicated at 18 and their opposite ends have threaded engagement with the other flange 15, the ends of the bolt being flush with the outer faces of the flanges.

65 The outer felly 12 is composed of a main section 20 extending nearly across the width of the completed felly and a complementary section 21. The coacting faces of the main section 20 and complementary section 21 are so formed that when the sections are applied 70 the correct positioning thereof is automatically insured, the main section 20 being shown in the present instance as provided with an annular V-shaped groove 23 which receives a V-shaped projection 24 formed 75 upon the complementary section 21. The main section 20 is provided with a marginal flange 25 and the complementary section 21 is provided with a similar flange 26 for a purpose hereinafter to appear. Each of 80

85 the main and complementary sections 20 and 21 has secured thereto an annular side plate 27 which is adapted to engage the corresponding face of the inner felly 11 and plate 13. The side plates 27 are provided with 90 alined pairs of apertures 28 adapted for the reception of bolts 29 whereby the side plates 27 and sections 20 and 21 of the outer felly 12 are held in position. The main section 20 of the outer felly 12 has formed in its 95

100

105

110

115

under surface, alined with each of the openings 28 thereof, transversely extending grooves 30.

A spring S is provided, formed of a continuous strip of spring metal bent to form substantially circumferentially extending portions 31 engaging the inner felly and similar portions 32 engaging the outer felly and staggered with relation to the portions 10 31, the corresponding ends of the portions being connected by crimped portions of the spring as indicated at 33. Each of the portions 31 and 32 is provided with a crimp or offset adapted to aline with a notch 16 or a 15 notch 30, and the portions of the springs 31 and 32 extend intermediate the bolts 17 and 29 respectively and these notches. If desired, wear plates 34 may be disposed intermediate the bolts 17 or 29, as the case may 20 be, and the spring, and intermediate the spring and the coacting face of its respective felly.

The sides of the plate 13 have formed therein grooves 35 adapted for the reception 25 of rings 36, a crimped spring 37 being disposed intermediate the ring and the interior of the groove and forcing the rings 36 outwardly for engagement with the side plates 27 whereby the entrance of dirt and water 30 between the side plates and the inner felly is effectually prevented.

In the assembly of my wheel, the spring S is first placed in position on the plate 13 intermediate the flanges 15 thereof and the 35 wear plates 34 if these are to be used, placed in position. The bolts 17 are then inserted and hold the spring firmly in position upon the inner felly. The main section 20 of the outer felly is then applied thereto, the wear 40 plates inserted and the bolts 29 placed in position to secure the spring to the main section. If desired, in placing the bolts 29 in position, anti-skid chain hooks H may be applied intermediate the heads thereof and the 45 plate 27. The tire T may then be applied with or without the removable rim R, and

the complementary section 21 placed in position. When the nuts are applied to the bolts 29, the tire or tire and rim as the case may be, will be firmly held in position. If skid 50 chain hooks are to be employed they may likewise be applied to the bolts 29 beneath the nuts thereof.

In the foregoing it will be obvious that I have constructed a wheel that is particularly well adapted for use by reason of its resilient qualities and by reason of the fact that construction of the same is such that not only may a tire be readily applied to and removed from the wheel, but the 55 longevity of the resilient element employed is materially increased by reason of the fact that the entrance of foreign matter tending to deteriorate the same is effectually prevented.

It will furthermore be obvious that the construction of the same as hereinabove set forth is capable of some change without materially departing from the spirit of my invention, and I accordingly do not limit myself to the specific structure hereinabove set forth except as hereinafter claimed.

What I claim is:

In a vehicle wheel, inner and outer fellies, flanges secured to the outer felly, a band secured to the inner felly and provided at the sides thereof with marginal flanges, circumferentially spaced transverse grooves formed in said band and outer felly and arranged in staggered relation to each other, 70 bolts mounted in said flanges and alined with the grooves in the band and outer felly, a cushioning spring disposed intermediate said inner and outer fellies and embodying alternate inner and outer felly engaging portions fitted in the grooves and between the fellies and bolts, and wear-plates disposed intermediate the bolts and spring and intermediate the spring and fellies.

In testimony whereof I hereunto affix my 90 signature.

JOHN E. GAREIS.
